FILLING MACHINE

Max Goldberg, New York, N. Y.

Application September 4, 1945, Serial No. 614,178

5 Claims. (Cl. 226—19)

1

This invention relates to a filling machine for filling containers with fibrous filling material, particularly of the air buoyant type, such as the downy covering of cattails known in the art as Typha material. Also for such filling materials as kapok, down and the like, and particularly into non-porous containers.

An object of this invention is to provide a filling machine in which containers are filled with material which is so light as to practically float in the air.

Another object of this invention is to provide a filling machine comprising a perforated cylinder reservoir having a shutter at its lower elevation and suction means in communication with the lower portion of the perforated cylinder reservoir whereby filling material is drawn into the cylinder while the air which carries the filling material is sucked out of the perforated cylinder through the perforations and leaving the filling material in a more densely packed form.

Another object of this invention is to provide an annular sleeve slidably mounted relative to the perforated cylinder and to provide weight means for raising the sleeve to uncover additional perforations as to permit additional suction surface in the perforated cylinder to be uncovered and so that additional quantities of filling material may be drawn into the perforated cylinder to densely pack the filling material.

Another object of this invention is to provide a cylindrical housing forming an annular chamber around the annular sleeve, the housing being elongated to permit considerable upward movement of the annular sleeve and to progressively uncover additional portions of the perforated cylinder whereby additional suction space is provided above the packed filling material.

Another object of this invention is to provide a power actuated disk-shaped plunger slidably mounted in the perforated cylinder whereby downward movement of the plunger will forcibly eject the packed filling material from the perforated cylinder reservoir into a container when a slidable shutter is opened in the lower portion of the perforated cylinder.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate

2

corresponding parts throughout the several views, in which:

Figure 1 is a top plan view of the filling machine.

5 Figure 2 is a cross-sectional view, the section being taken as on line 2—2 in Figure 3.

Figure 3 is a central vertical cross-sectional view, the section being taken as on line 3—3 in Figure 1.

10 Figure 4 is a fragmentary cross-sectional view, the section being taken as on line 4—4 in Figure 1.

In the illustrated embodiment of the invention, the numeral 10 indicates a filling machine 15 for filling containers such as cushions, pillows, etc., with material which is so light as to practically float in the air.

The filling machine 10 comprises a hollow cylinder 11 having perforations 12 extending all around its surface from an inlet 13 at its upper end to substantially its lower end. A hopper 14 is operatively connected with the opening 13. At its lower end the cylinder 11 is slotted to receive a shutter 15 in slidable engagement.

25 An annular member 17 having an inner diameter corresponding to the outer diameter of the cylinder 11 is slidably mounted on the cylinder. Cables 18 passing over sheaves 19 have their lower ends connected to the annular member 17.

30 The cables 18 pass over the sheaves 19 and over a sheave 20 and are connected to a counter-weight 21 of a size sufficient to balance the weight of the annular member 17.

A hollow member 23 circumscribes the perforated hollow cylinder 11 and provides an annular chamber 24 in which the annular member 17 is slidably mounted. The upper wall 25 of the hollow member 23 extends above the top-most perforations in the cylinder 11. The lower wall 25' of the hollow member 23 extends below the lowermost perforation in the cylinder 11.

35 A suction means such as a centrifugal blower 26 has its suction inlet connected with the lower end of the hollow member 23 and communicates 40 with the lowermost perforations 12 beneath the slidable annular member 17.

45 A disk-shaped piston 27 having a piston rod 28 is slidably mounted in the perforated cylinder 11. The upper portion of the rod 28 is formed to provide a rack gear 29. A pinion gear 30 is in meshed engagement with the rack gear 29.

50 A cylindrical sleeve valve 39 is slidably mounted in the cylinder 11. The sleeve valve 39 is mounted in frictionally contacting relation on the piston 55 27. Arms 40 extend upwardly from the sleeve

valve 39 and have lateral extensions 41 of a size adapted to engage the upper wall of the cylinder 11. An electric motor 35 is suitably supported on the upper portion of the cylinder 11 by a bracket 36. A motor shaft 37 is connected with the pinion gear 30. A bearing 38 supports the free end of the shaft 37. The arms 40 limit the downward movement of the sleeve valve. The sleeve valve 39 moves down sufficiently to close the passage or inlet 13 to the hopper 14. The annular member 17 causes the suction to be concentrated through the apertures 12 positioned below its lower surface.

In operation, the slidable shutter 15 stays in closed position until the entire perforated collecting reservoir is filled. The shutter 15 is then opened. The power driven piston 27 is lowered by the motor 35. The lowered piston 27 permits the sleeve valve 39 to follow its motion downwardly to close the inlet 13. The piston 27 ejects the filled material in the reservoir 11 into a container 42 such as is used on pillows, cushions, etc. The container 42 is suitably secured to a nozzle 43 at the lower end of the cylinder 11.

The suction causes the filling material to fill up that portion of the casing 11 which is below the annular member 17. As the additional member 17 is raised, additional perforations 12 above the aforementioned perforations communicate with the suction 26 and the material piles up in the cylinder 11 until the annular member is up at its uppermost position, when the cylinder is entirely filled.

During operation, the annular member 17 is raised in any suitable manner such as by pulling down the counterweight 21. When the member 21 is raised, the sleeve valve 39 follows the upward movement of the said member. The filling material is fed into the hopper 14 and enters the casing 11 through the inlet 13 due to the air suction through the apertures 12 below the annular member 17.

As the filling material is being ejected into the container 42, the suction is directed into the container through the interstices in the filling material and through the perforations 12.

The air displaced by the filling material from the container 42 is removed by the suction means 26. The air passes outwardly from the container through the interstices between the fibers, thence through the nozzle 43 and through the perforations 12 and into the chamber 24 and out through the suction means 26.

It is to be noted that one of the important effects resulting from the use of this invention resides in the fact that there is always an inward draft of air in toward the machine from the external atmosphere so that if any of the buoyant material tends to escape from the machine or from the container being filled it is drawn back by the inward suction towards the machine and keeps the surrounding atmosphere clear of the floating material and accompanying dust for the operator to work in. It is to be noted that the outlet of the suction blower is piped outdoors or to a dust collecting bin.

For the purpose of supporting the shutter 15 in open position, there is provided a pair of slides 45 having grooves 46 in which the shutter is slidably mounted.

In accordance with the patent statutes I have described and illustrated the preferred embodiment of my invention, but it will be understood that various changes and modifications can be made therein without departing from the spirit of the invention as defined by the appended claims.

I claim:

1. In a filling machine for filling containers with air buoyant filling material, comprising a perforated cylinder reservoir having an inlet for filling material at its upper end, a piston for ejecting the material from said cylinder, a sleeve valve following the movements of said piston for part of its stroke and being slidable in said cylinder for closing said inlet, said cylinder having a slidable shutter at its lower end, suction means in communication with the lower portion of said perforated cylinder reservoir, an annular sleeve slidably mounted parallel with the axis of said perforated cylinder, means for raising said sleeve, to uncover additional perforations in said perforated cylinder and augment the suction surface whereby additional filling material is permitted to be drawn into said perforated cylinder reservoir in densely packed form.

2. In a filling machine for filling containers with air buoyant material, comprising a perforated cylinder reservoir having a hopper and an inlet for filling material at its upper end and a slidable shutter at its lower end, suction means in communication with the perforated surface in the lower portion of said perforated cylinder reservoir, an annular sleeve contacting with and being slidably mounted parallel with the axis of said perforated cylinder, means for raising said sleeve to successively uncover additional perforations in said perforated cylinder and augment the suction surface whereby additional filling material is permitted to be drawn from said hopper into said perforated cylinder reservoir and deposited therein in densely packed form and piston means movable in said cylinder for ejecting said filling material, said cylinder having a sleeve valve following the movements of said piston means for part of its stroke and being slidable in said cylinder for closing said inlet.

3. In a filling machine for filling containers with substantially air buoyant material, comprising a perforated cylinder reservoir having a hopper and an inlet for filling material at its upper end and a slidable shutter for closing its lower end, an annular sleeve contacting with and being slidably mounted parallel with the axis of said perforated cylinder, stop means for limiting the downward movement of said sleeve for uncovering the lowermost portion of said perforated cylinder, suction means in communication with said uncovered portion of said perforated cylinder reservoir, means for raising said sleeve to successively uncover additional perforations in said perforated cylinder and augment the suction surface whereby additional filling material is permitted to be drawn from said hopper into said perforated cylinder reservoir and deposited therein in densely packed form and piston means movable in said cylinder for ejecting said filling material, said cylinder having a sleeve valve following the movements of said piston means for part of its stroke and being slidable in said cylinder for closing said inlet.

4. In a filling machine for filling containers with substantially air buoyant material, comprising a perforated cylinder reservoir having a hopper and an inlet for filling material at its upper end and a slidable shutter for closing its lower end, a slidable member mounted in said cylinder for closing said inlet, an annular sleeve in slidable contact with the outer surface of said perforated cylinder and being mounted parallel with the axis of said perforated cylinder, stop means for limiting the downward movement of

said sleeve for uncovering the lowermost portion of said perforated cylinder reservoir, suction means in communication with said uncovered portion of said perforated cylinder reservoir, means for raising said sleeve to successively uncover additional perforations in said perforated cylinder and augment the suction surface whereby additional filling material is permitted to be drawn from said hopper into said perforated cylinder reservoir and deposited therein in densely packed form, said perforated cylinder having a nozzle at its lower end and piston means movable in said cylinder for ejecting said filling material into said nozzle when said shutter is moved into open position.

5. In a filling machine for filling containers with substantially air buoyant material, comprising a perforated cylinder reservoir having a hopper and an inlet for filling material at its upper end and a slideable shutter for closing its lower end, a closure member slideably mounted in said cylinder for closing said inlet, means for limiting the motion of said closure member, an annular sleeve in slideable contact with the outer surface of said perforated cylinder and being enclosed within an annular chamber outside said perforated cylinder, stop means for limiting the downward movement of said sleeve for uncovering the lowermost portion of said perforated cylinder reservoir, suction means in communica- 30

tion with said uncovered portion of said perforated cylinder reservoir, means for raising said sleeve to successively uncover additional perforations in said perforated cylinder and augment the suction surface whereby additional filling material is permitted to be drawn from said hopper into said perforated cylinder reservoir and deposited therein, said perforated cylinder having a nozzle at its lower end, and piston means movable in said cylinder for ejecting said filling material into said nozzle when said shutter is moved into open position, said piston means having a piston rod extending upwardly therefrom, said closure member having a central aperture and being slideable with said piston, said closure member being gravitationally movable to inlet closing position when said piston is moved into said cylinder.

MAX GOLDBERG.
